UNITED STATES PATENT OFFICE.

JOHN L. HENRY, OF ALBANY, TEXAS.

SCOOTER FIGURE WHEELED TOY.

Application filed June 3, 1926, Serial No. 113,384. Renewed February 28, 1928.

This invention relates to a figure wheeled toy.

- The principal object of the invention comprehends generically the provision of a figure wheeled toy built and designed to simulate or represent the construction and propulsion of a vehicle of the so-called scooter type, and comprehends more particularly the provision of a scooter vehicle toy embodying a scooter vehicle and an articulated toy figure simulating an occupant of the vehicle mounted thereon, the vehicle and toy figure occupant being operable to simulate occupant-propelling activity of the scooter vehicle.
- Further and ancillary objects of the invention include the provision of a simulated scooter vehicle in which the articulated toy figure is movable in natural semblance of a scooter occupant or operator; and the further provision of a scooter toy embodying a scooter frame and a mechanically operated figure thereon, designed so as to be capable of being manufactured at low cost and durably operated with efficiency.
- To the accomplishment of the foregoing and such other objects as will hereinafter appear, my invention consists in the elements and their relation one to the other as more particularly described hereinafter, reference being had to the accompanying drawings which show the preferred embodiments of my invention, and in which:

Figs. 1 to 4 are views of one form of figure wheeled toy embodying the principles of my invention, of which Fig. 1 is a perspective view, and Figs. 2-4 are side elevational views showing the parts in sequential operated positions; and

Figs. 5 and 6 are views of a modified form of the invention, of which Fig. 5 is a perspective view and Fig. 6 a side elevational view.

Referring now more in detail to the drawings and having reference first to the form of the invention shown in Figs. 1-4 thereof, the figure wheeled toy of my invention comprises a vehicle generally designated as A, simulating a scooter, a toy figure generally designated as B simulating a standing occupant of the vehicle, mounted on the scooter frame, and an operating means generally designated as C for operating the vehicle A and occupant figure B to simulate an occupant-propelling activity of the scooter.

The simulated scooter vehicle A comprises in its most simple form a frame including a

running or standing board 10 preferably elongated after the manner of a scooter frame beard, a post 11 fixed forwardly to said running board 10 and simulating a steering post, said post being provided with the steering cross bar 12, the running board 10 being supported on a plurality of wheels, preferably three in number, including the rear wheel 13 journaled in a fork 14 attached to the running board 10 and a pair of front wheels 15 and 16 fixed to an axle 17, which axle is journaled in the scooter frame, as for example in the lower part of the simulated steering post 11.

The occupant figure B comprises in the preferred construction a body member 18 preferably movable in a vertical plane between a forward crouching position shown in Fig. 2 of the drawings and a more erect position shown in Fig. 4 of the drawings, a pair of arm members 19, 19 connecting the body member 18 with the steering cross bar 12 of the simulated steering post 11, the figure further including a leg member 20 connecting the body member with the running board 10 and a second leg member 21 movably connected to the body member and mounted free of said running board, said second leg member being movable between forward and rearward positions illustrated by Figs. 2 and 4 of the drawings to simulate propelling contact with a support such as 3 on which the toy is placed.

Preferably the arm members 19, 19 connect the body member of the figure with the simulated steering post so as to permit a to-and-fro oscillation of the body, and to accomplish this these arm members are mounted so as to be freely pivotable at one end on a pivot rod 22 extending through the body and arm members and at the other end on the steering cross bar 12. The leg member 20 in the form of the invention shown in Figs. 1-4 comprises two leg portions 20' and 20² joined at 23, the lower leg portion 20² being fixed to the running board 10 and the upper leg section 20' being pivotally connected to the body member 18 on the pivot rod 24. Preferably the joint between the leg portions is so designed, as shown in the drawings, as to permit a bending action at the knee only in one direction in correct simulation of a knee joint.

The leg member 21 may similarly comprise an upper leg portion 21' and a lower leg portion 21², the upper leg portion being movably mounted on a pivot rod 24 and the lower leg

portion being joined as at 25 to the upper leg portion, the joint being similar to that provided in the leg member 20 so as to effect a correct simulation of a knee joint. This is produced by providing interlocking tongue and grooves at the joint and by shaping or contouring the leg members at the joint, as clearly shown in the drawings. The leg member 21 is, as aforesaid, movably mounted so as to simulate propelling contact with the support *s*, and to this end the lower leg portion 21² is arranged to be freely movable at a side of the running board 10, the foot portion of the same extending below the running board and being movable so as to simulate contact with the ground or support.

The operating means C for effecting simulated propelling action of the figure comprises means for oscillating the body of the figure between a forward crouching position (Fig. 2) and a more erect position (Fig. 4) and for moving the leg member 21 between a forward position (Fig. 2) and a rearward position (Fig. 4), the operation being such that the leg member is moved forwardly with the movement of the body member to the forward crouching position and is moved rearwardly with the movement of the body member to the more erect position.

In the form of the invention shown in Figs. 1-4, the operating means comprises a connecting rod 26 connecting the body member 18 with the vehicle wheels, the wheel axle 17 having a crank portion 27 connected to one end of the rod 26 and the body member 18 having a pin 28 connected to the other end of the rod 26. For operating the leg member 21 the upper leg portion 21¹ thereof is connected to a part of the scooter frame, this being accomplished by the provision of a connecting rod 29 connected at one end to the steering cross bar 12 and at the other end to a point in the leg portion 21¹ below the pivot rod 24.

By means of this recited construction, it will be seen that when the vehicle is propelled along the ground, as by means of a draw string 30 which may be connected to a brace rod 31 fixed at its opposite ends to the post 11 and the axle 17, the figure B will be operated by rotation of the crank axle 17, the body of the figure being movable between the forwardly inclined or crouching position and the more erect position shown in Figs. 2-4 of the drawings, and the freely movable leg member 21 will be simultaneously moved between the forward knee bended position shown in Fig. 2 and the rearward leg straightened position shown in Fig. 4 of the drawings, a life-like resemblance of occupant-propelling activity of the scooter being thereby effected.

Referring now to Figs. 5 and 6 of the drawings, in which I show a modified form of the invention, the scooter vehicle A' also com-

prises a three-wheeled structure having a running board 32 mounted on a rear wheel 33 and a front axle structure 34 having the running wheels 35 and 36, the said scooter vehicle also including the simulated steering post 37 provided with the steering cross bar 38.

In this form of the invention the toy figure generally designated as B' comprises a body member 39 movable in a manner similar to that heretofore described in connection with Fig. 4 of the drawings, said body member being provided with the arm members 40 and 41 pivotally connecting the body member with the cross bar 38, said body member being further provided with a leg member 42 connecting the body member with the running board 32 and a second leg member 43 pivotally mounted on the body member 39 and movable at the side of the running board 32 in similar contact with the running surface of the vehicle.

In this modified form of construction the leg member 42, in lieu of being fixed to the running board, is pivotally connected thereto as at 44. The leg sections of both leg members are not jointed, as shown in the form of the invention of Figs. 1-4, but are rigidly mounted in bended positions, this being obtained preferably by connecting the leg sections by means of a stiffening member such as a wire 44' received in axial bores provided in the leg sections.

The operating means C' of the modified form of construction comprises a cam loop 45 fixed at 46 to the leg member 42 and arranged so as to lie adjacent the inner face of the front wheel 36, and so as to be engaged by a pin 47 fixed to so as to be rotatable with the front wheel 36. By means of this construction it will be seen that the cam loop 45 is intermittently engaged during the rotation of the propelling wheel 36, such intermittent engagement effecting the oscillation of the body of the figure B' between a crouching or forwardly inclined position and a more erect position, the body being movable relatively to the arm members 40 and 41 and the leg member 42. For operating the leg member 43 the same is connected at a point 48 below the pivot point of the leg member to the steering post 37 by means of a connecting rod 49, the connection being such that the leg member is moved between forward and rearward positions, the forward position being assumed when the figure body is in the forwardly inclined position and the rearward position being assumed when the figure body is in the more erect position.

The manner of making and using the figure wheeled scooter toy of my invention will in the main be fully apparent from the above detailed description thereof. It will be further apparent that many changes and modifications may be made in the structure dis-

closed without departing from the spirit of my invention, defined in the following claims.

I claim:

1. A figure wheeled toy comprising a simulated scooter vehicle embodying a frame having a running board and wheels carried by the frame, an articulated toy figure simulating an occupant of the vehicle mounted on the scooter vehicle, said toy figure including a body member, a leg member connecting the body member to the running board and a second leg member connected to the body member and mounted free of said running board, said second leg member being movably mounted so as to simulate propelling contact with a support on which the toy is placed, and means whereby propulsion of the vehicle along the support causes the articulated figure toy to move to simulate occupant-propelling activity.
2. A figure wheeled toy comprising a simulated scooter vehicle embodying a frame having a running board and wheels carried by the frame, an articulated toy figure simulating a standing occupant of the vehicle mounted on the scooter vehicle, said toy figure including a body member, and a leg member connected to the body member and mounted free of said running board, said leg member being movably mounted so as to simulate propelling contact with a support on which the toy is placed, and means for operating said vehicle and figure to simulate occupant-propelling activity.
3. A figure wheeled toy comprising a simulated scooter vehicle embodying a frame having a simulated steering post and an elongated running board and wheels carried by the frame, an articulated toy figure simulating a standing occupant of the vehicle mounted on the scooter vehicle, said toy figure including a body member, arm members connecting the body member to the steering post, and a leg member connected to the body member and mounted free of said running board, said leg member being movably mounted so as to simulate propelling contact with a support on which the toy is placed, and means for operating said vehicle and figure to simulate occupant-propelling activity.
4. A figure wheeled toy comprising a simulated scooter vehicle embodying a frame having a running board and wheels carried by the frame, an articulated toy figure simulating a standing occupant of the vehicle mounted on the scooter vehicle, said toy figure including a body member, a leg member connecting the body member to the running board and a second leg member connected to the body member and mounted free of said running board, said second leg member being movably mounted so as to simulate propelling contact with a support on which the toy is placed, and means connecting the articulated figure with the wheels operative for causing the body member and leg member of said figure to oscillate relatively to each other and to said frame to simulate occupant-propelling activity when the vehicle is propelled along the support.
5. A figure wheeled toy comprising a simulated scooter vehicle embodying a frame having a running board and wheels carried by the frame, an articulated toy figure simulating a standing occupant of the vehicle mounted on the scooter vehicle, said toy figure including a body member movable in a vertical plane, and a leg member movably connected to the body member and mounted free of said running board, said leg member being mounted so as to simulate propelling contact with a support on which the toy is placed, and means for operating said vehicle and figure to cause the body member and said leg member of said figure to move relatively to each other and to said frame to simulate occupant-propelling activity.
6. A figure wheeled toy comprising a simulated scooter vehicle embodying a frame having a running board and wheels carried by the frame, an articulated toy figure simulating a standing occupant of the vehicle mounted on the scooter vehicle, said toy figure including a body member oscillatable to and fro in a vertical plane, a leg member connecting the body member to the running board and a second leg member pivotally connected to the body member and mounted free of said running board, said second leg member being mounted so as to simulate propelling contact with a support on which the toy is placed, and means for operating said vehicle and figure to cause the body member and second leg member of said figure to oscillate and move relatively to each other and to said frame to simulate occupant-propelling activity.
7. A figure wheeled toy comprising a simulated scooter vehicle embodying a frame having a running board and wheels carried by the frame, an articulated toy figure simulating a standing occupant of the vehicle mounted on the scooter vehicle, said toy figure including a body member oscillatable to and fro in a vertical plane, a leg member supportingly connecting the body member to the running board and a second leg member pivotally connected to the body member and mounted free of said running board, said second leg member being mounted so as to simulate propelling contact with a support on which the toy is placed, and means connecting the movable members of said figure with the vehicle wheels operative for causing the body member and leg member of said figure to oscillate relatively to each other and to said frame to simulate occupant-propelling activity when the vehicle is propelled along the support.
8. A figure wheeled toy comprising a simulated scooter vehicle embodying a frame

having a running board and wheels carried by the frame, an articulated toy figure simulating a standing occupant of the vehicle mounted on the scooter vehicle, said toy figure including a body member movable to and fro in a vertical plane, and a leg member movably connected to the body member and mounted free of said running board, said leg member being mounted so as to be movable to simulate propelling contact with a support on which the toy is placed, and means connecting the body member with the vehicle wheels for operating the body member and said leg member of said figure to move to simulate occupant-propelling activity.

9. A figure wheeled toy comprising a simulated scooter vehicle embodying a frame having a simulated steering post and an elongated running board and wheels carried by the frame, an articulated toy figure simulating a standing occupant of the vehicle mounted on the scooter vehicle, said toy figure including a body member oscillatable in a vertical plane, arm members connecting the body member to the steering post, a leg member connecting the body member to the running board and a second leg member movably connected to the body member and mounted free of said running board, said second leg member being mounted so as to be movable to simulate propelling contact with a support on which the toy is placed, and means connecting the body member with the vehicle wheels for oscillating the same and for operating the members of the figure to simulate occupant-propelling activity.

10. A figure wheeled toy comprising a simulated scooter vehicle embodying a frame having a simulated steering post and an elongated running board and wheels carried by the frame, an articulated toy figure simulating a standing occupant of the vehicle mounted on the scooter vehicle, said toy figure including a body member oscillatable in a vertical plane, arm members connecting the body member to the steering post, a leg member connecting the body member to the running board and a second leg member movably connected to the body member and mounted free of said running board, said second leg member being mounted so as to be movable to simulate propelling contact with a support on which the toy is placed, means connecting the body member with the vehicle wheels and means connecting the leg member with the vehicle frame, said means being related so that movement of the vehicle along the support simultaneously moves the body member to the forward crouching position and the leg member to the forward position and simultaneously moves the body member to the more erect position and the leg member to the rearward position.

necting the body member with the vehicle wheels for oscillating the same and means connecting the second leg member with the steering post for moving the leg member when the body member is oscillated.

11. A figure wheeled toy comprising a simulated scooter vehicle embodying a frame having a running board and wheels carried by the frame, a toy figure simulating a standing occupant of the vehicle mounted on the scooter vehicle, said figure including a body member movable between a forward crouching position and a more erect position, and a leg member movably connected to the body member and mounted free of said running board, said leg member being movable between forward and rearward positions to simulate propelling contact with a support on which the toy is placed, and means for operating said figure to move the leg member forwardly with the movement of the body member to the forward crouching position and to move the leg member rearwardly with the movement of the body member to the more erect position.

12. A figure wheeled toy comprising a simulated scooter vehicle embodying a frame having a running board and wheels carried by the frame, a toy figure simulating a standing occupant of the vehicle mounted on the scooter vehicle, said figure including a body member movable between a forward crouching position and a more erect position, and a leg member movably connected to the body member and mounted free of said running board, said leg member being movable between forward and rearward positions to simulate propelling contact with a support on which the toy is placed, means connecting the body member with the vehicle wheels and means connecting the leg member with the vehicle frame, said means being related so that movement of the vehicle along the support simultaneously moves the body member to the forward crouching position and the leg member to the forward position and simultaneously moves the body member to the more erect position and the leg member to the rearward position.

Signed at Brandon, in the county of Rutland and State of Vermont, this 28th day of May, A. D. 1926.

JOHN L. HENRY.
